(57) **CLAIM**

The new and ornamental design for an ornamental strip for attachment to a motorcycle helmet, as shown and described.

DESCRIPTION

FIG. 1 is a perspective view of an ornamental strip for attachment to a motorcycle helmet showing my new design; and,

FIG. 2 is a side view thereof.

The helmet shown in broken lines is for illustrative purposes only and forms no part of the claimed design.

1 Claim, 2 Drawing Sheets

FIG.2
